UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

UNDERFEED STOKER.

Application filed April 19, 1923. Serial No. 633,095.

My invention relates to underfeed stokers and more particularly to underfeed stokers of the inclined multiple retort type.

The principal object of the invention is to provide novel and improved means for controlling the admission of air to the air supplying surfaces of the underfeed section of stokers of the type above indicated.

The following is a description of my invention, reference being had to the accompanying drawings, in which,—

Figure 1 is a longitudinal sectional view of a portion of an underfeed stoker embodying the features of the invention in their preferred form;

Fig. 2 is a transverse sectional view, on an enlarged scale, taken on the line 2—2 of Fig. 1;

Fig. 3 is a longitudinal sectional view of a portion of an underfeed stoker having a modified form of means for controlling the supply of air to the fuel supporting surfaces;

Fig. 4 is a transverse sectional view, on an enlarged scale, taken on the line 4—4 of Fig. 3; and

Fig. 5 is a detail view in perspective of a component part of the structure shown in Figs. 3 and 4.

The stoker illustrated in the drawings is provided with a plurality of downwardly inclined fuel retorts 2 and tuyère boxes 4 alternately arranged, and a wind box 6 located beneath the fuel retorts and tuyère boxes for supplying air to the tuyère boxes. The retorts 2 are each provided with a bottom wall 8 and vertical side walls 10, the latter also constituting the side walls of the tuyère boxes. The upper and lower edges of each of the side walls 10 are provided with flanges 12 and 14, respectively, that project inwardly toward the centers of the tuyère boxes. A series of tuyère blocks 16 is supported on the flanged upper edges of the side walls 10 so as to form the tops of the tuyère boxes.

In the construction illustrated in Fig. 1, each tuyère box is provided with upper and lower end walls 18 and 20, respectively, and with three transverse partitions 22 that divide the tuyère box into four compartments.

The partitions 22 extend between the vertical sides 10 of the tuyère box and each is provided with a forwardly projecting base portion 24 that rests upon the lower flanges 14 of the sides 10. The base portions 24 serve as baffles or air obstructing plates to partially close the openings in the underside of the three upper compartments of each tuyère box, and the opening in the underside of the lowermost compartment is partially closed by a suitably curved wall or baffle plate 26.

It will be apparent that by varying the relative width of the base portions of the partitions and the plate 26, the supply of air to the several groups of tuyère blocks may be relatively varied as desired. One advantage of this provision for controlling the supply of air to the several groups of tuyère blocks of each individual tuyère box is that different kinds of fuels require different air supply under different parts of the fuel bed. For instance, when bituminous fuels are burned in a stoker of this type, a gradually decreasing air supply toward the rear end of the stoker is desired, but when burning waste fuels, such as coke breeze, or low grade fuels such as lignite, the opposite is desired. Also this construction permits individual control of air to be secured for each tuyère box which is of particular advantage in relatively wide stokers.

As shown, the partitions 22 are removably mounted on the flanges 14 and are adapted to be relatively adjusted longitudinally of the flanges within certain limits, so as to vary the number of tuyère blocks in each of said groups. To provide for this the base portions 24 of the partitions are provided with depending lugs 28 that are adapted to be received in a series of notches 30 in each of the flanges 14. If desired, however, the partitions 22 may be cast integral with the side walls of the tuyère boxes.

The supply of air to the different groups of tuyère blocks may also be varied by means of transverse baffles or air obstructing plates 32 that are removably mounted on the flanges 14 and are adapted to be adjusted longitudinally of the flanges by means of de-

pending lugs 34 on the under sides of the ends thereof which are received in the slots 30. Such adjustment of the plates 32 is desirable in some cases when it is desired 5 to adjust the partitions 22.

In the construction illustrated in Figs. 3, 4 and 5 of the drawings each tuyère box is provided with three partitions 36 that divide the box into four compartments that 10 are similar to the compartments of the construction illustrated in Fig. 1. The openings in the under sides of these compartments are partially closed by transverse baffle plates 38, and a sliding damper 40 is 15 arranged to slide longitudinally along the under sides of the transverse plates 38. The damper 40 is provided with transverse portions 42 which are so positioned with relation to the bars 38 that when the damper 20 is in its extreme lowermost position, as shown in Fig. 3 of the drawings, a greater supply of air will be admitted to the uppermost than to the lowermost compartment and that upon sliding the damper to its extreme upper position the opposite result is 25 secured, the supply of air to the intermediate compartments being varied accordingly. The damper for each tuyère box is adapted to be conveniently operated outside 30 of the furnace, by means of a rack 44 on the under side of each damper which is engaged by a pinion 46 on the inner end of a shaft 48 that extends through the outer wall of the furnace and is provided with an operating crank 50 on its outer end.

In the construction illustrated in Fig. 1 the wind box is divided into two compartments by means of a transverse partition 52 and air is separately supplied to these compartments through ducts 54, respectively, having controlling dampers 56. This construction permits a higher air pressure to be secured in the front compartment than in the rear or vice versa, air being supplied 45 to the ducts 54 under different pressures.

As will be evident to those skilled in the art my invention permits of various modifications without departing from the spirit thereof or the scope of the appended claims.

50 What I claim is:

1. An underfeed stoker having, in combination, a plurality of downwardly inclined fuel retorts and tuyère boxes alternately arranged, the tuyère boxes having fuel supporting tuyères, and means for relatively varying the supply of air to different groups of tuyères of one tuyère box independently of the other tuyère boxes.

60 2. An underfeed stoker having, in combination a plurality of downwardly inclined fuel retorts and tuyère boxes alternately arranged, the tuyère boxes having fuel supporting tuyères, partitions dividing each tuyère box transversely into a plurality of compartments, and means for relatively

varying the supply of air to different compartments of one tuyère box independently of the other tuyère boxes.

3. An underfeed stoker having, in combination, a plurality of downwardly inclined 70 fuel retorts and tuyère boxes alternately arranged, the tuyère boxes having fuel supporting tuyères, and means comprising partitions within each tuyère box for controlling the supply of air to different groups of 75 tuyères, said partitions being adapted to be independently adjusted longitudinally of the tuyère boxes.

4. An underfeed stoker having, in combination, a plurality of downwardly inclined 80 fuel retorts and tuyère boxes alternately arranged, the tuyère boxes having fuel supporting tuyères, and means for controlling the supply of air to different groups of 85 tuyères of each tuyère box independently of the other tuyère boxes comprising transverse partitions in each tuyère box, and air obstructing plates extending between longitudinal sides of each tuyère box and positioned between the partitions. 90

5. An underfeed stoker having, in combination, a plurality of downwardly inclined fuel retorts and tuyère boxes alternately arranged, the tuyère boxes having fuel supporting tuyères, and means for supplying 95 air under different pressures to different groups of tuyères, respectively, of one tuyère box independently of the other tuyère boxes.

6. An underfeed stoker having, in combination, a plurality of downwardly inclined fuel retorts and tuyère boxes alternately arranged, the tuyère boxes having fuel supporting tuyères, partitions transversely arranged in each tuyère box dividing the 100 tuyère box into a plurality of compartments, a wind box located beneath the retorts and tuyère boxes for supplying air to the tuyères through openings in the under sides of said compartments, and means for relatively 105 varying the size of said openings in said compartments so as to relatively vary the supply of air to said compartments of each tuyère box independently of the air supply to the other tuyère boxes. 110

7. An underfeed stoker having, in combination, a plurality of downwardly inclined fuel retorts and tuyère boxes alternately arranged, the tuyère boxes having fuel supporting tuyères, and means for controlling 115 the supply of air to different groups of tuyères of each tuyère box comprising transverse partitions in each tuyère box having laterally extending air obstructing base portions, and air obstructing plates positioned 120 between said partitions and removably mounted on the lower longitudinal edge portions of the longitudinal sides of said tuyère boxes.

8. An underfeed stoker having, in combi- 130

nation, a plurality of downwardly inclined fuel retorts and tuyère boxes alternately arranged, the tuyère boxes having fuel supporting tuyères, a transverse partition dividing each tuyère box into two compartments, a wind box beneath the retorts and tuyère boxes, a partition dividing the wind box into two compartments, the two compartments of each tuyère box being respectively in communication with the two compartments of said wind box, and means for establishing communication between said compartments of the wind box and separate sources of compressed air supply, respectively.

EDWIN LUNDGREN.
